(57) **CLAIM**

The ornamental design for a notepad holder, as shown and described.

DESCRIPTION

FIG. 1 shows a view in perspective from above and one side of the notepad holder;

FIG. 2 shows a plan view from above of the notepad holder of FIG. 1;

FIG. 3 shows a view in front elevation of the notepad holder of FIG. 1;

FIG. 4 shows a view in elevation from one side of the notepad holder of FIG. 1, the opposite side being a mirror image of FIG. 4;

FIG. 5 shows an underneath plan view of the notepad holder of FIG. 1; and,

FIG. 6 shows a view in rear elevation of the notepad holder of FIG. 1.

The fragmentary shading pattern on the surface of the notepad holder particularly in FIGS. 2, 3, 5, and 6 is understood to represent a uniform surface finish rather than the particular configuration shown on the surface in these figures.
